UNITED STATES PATENT OFFICE.

OSWALD H. HANSEN, OF FORT WASHINGTON, WISCONSIN, ASSIGNOR TO HANSEN CANNING MACHINERY CORPORATION, OF CEDARBURG, WISCONSIN, A CORPORATION OF WISCONSIN.

BEET TOPPER.

Application filed August 18, 1924. Serial No. 732,875.

This invention relates in general to improvements in the art of removing superfluous appendages from tuberous edible substances, and relates more specifically to improvements in the construction and operation of mechanisms for automatically and effectively removing husks, leaves and other undesirable vegetation from farm products such as corn, beets and the like.

An object of the invention is to provide a machine for removing superfluous appendages from corn, beets, and the like, which is simple in construction and efficient in operation. Another object of the invention is to provide compact mechanism adapted to husk corn, top beets, or to perform similar operations, having enormous capacity and which is capable of effectively removing the superfluous material without damaging the valuable portions of the objects treated. A further object of the invention is to provide improved means for protecting the relatively frail elements of husking and topping machines, and for insuring automatic and efficient lubrication of all of the bearings of such mechanisms. Still another object of the invention is to provide a simplified rigid frame structure for husking and topping machines and to equip such devices with simpler and more efficient means for guiding the objects therethrough. Another object of the invention is to provide improved driving mechanism for topping and husking machines, and also to provide instrumentalities for facilitating rapid assemblage and dismantling of mechanisms of this class. A further object of the invention is to provide various improvements in topping and husking mechanisms, which will reduce to a minimum the cost of manufacture and operation and which will enhance to a maximum the efficiency thereof. These and other objects and advantages of the improvement will be apparent in the course of the following description.

Several of the novel features of topping and husking machine structure disclosed but not specifically claimed herein, form the subject of copending applications Serial No. 670,429, filed October 24, 1923, and Serial No. 687,191, filed January 19, 1924.

A clear conception of an embodiment of the present invention and of the operation of mechanisms constructed in accordance

therewith may be had by referring to the drawing accompanying and forming a part of this specification in which like reference characters designate the same or similar parts in the several views.

Fig. 1 is a longitudinal vertical section taken through one of the rolls of an improved topping or husking machine.

Fig. 2 is a top view of the improved topping or husking machine.

Fig. 3 is a fragmentary enlarged transverse section through the improved topping or husking machine, the section being taken in the plane of the axis of the main driving shaft.

Fig. 4 is a transverse section through the rolls, distributing flap and guiding walls of the improved topping or husking machine.

Fig. 5 is a fragmentary enlarged longitudinal section through the lower roll supporting structure and a fragment of one of the rolls.

Fig. 6 is a fragmentary enlarged longitudinal section through the upper roll supporting and driving structure and a fragment of one of the rolls.

While the invention is disclosed herein as being specifically applied to a beet topping machine, it should be understood that the improvement is capable of more general application to machines for automatically treating other objects, such as corn in the husks, and that the specific disclosure made herein is not to be considered as an intentional limitation of the scope of the invention.

The beet topping machine specifically illustrated in the drawing comprises in general a stationary main frame 24 consisting of a pair of identical side frames and a plurality of elements connecting the same; a pair of identical oppositely rotatable parallel fluted inclined rolls 2, 3 located above the frame 24; a pair of stationary parallel longitudinally inclined roll supporting shafts 7, 8 detachably mounted in fixed supports 21, 22 associated with the frame 24; a hopper consisting of inclined side plates 10, 11 for confining and guiding the beets 5 along the rolls 2, 3; a one-piece supply chute 14 for delivering the beets 5 into and along the guiding hopper; mechanism for continuously rotating the rolls 2, 3 upon their respective supporting shafts 7, 8; and improved de-

VICES FOR SUPPORTING, HOUSING AND LUBRICATING THE DRIVING MECHANISM.

The fluted rolls 2, 3 are preferably of identical form being provided with end 5 bores and intermediate grease confining chambers 32 connecting the bores. As shown in Fig. 4, the rolls 2, 3 are of uniform star-shaped cross-section throughout their 10 lengths, the ridges and grooves of the rolls intermeshing during rotation thereof.

The stationary inclined roll supporting shafts 7, 8 coat with the end bores of the rolls 2, 3 respectively, and are provided at their opposite ends with lubricating ducts 15 for insuring proper lubrication from grease cups of the bearing surfaces between the rolls 2, 3 and the shafts 7, 8. The supporting shafts 7, 8 are detachably secured to the lower stationary supports 21 in any suitable 20 manner and have thrust collars 31 detachably secured thereto. The thrust collars 31 coat with lower end surfaces of the rolls 2, 3 and are preferably located entirely within recesses formed in the lower roll ends 25 in order to protect the thrust bearings and to prevent entry of dirt, see Fig. 5.

The roll driving mechanism comprises gears 25, 20 detachably associated with the upper extremities of the rolls 2, 3 respectively and rotatably supported upon the shafts 7, 8 respectively; coaxial helical gears 12, 13 meshing with the gears 25, 20 respectively; a main horizontal driving shaft 15 drivingly associated with the gears 12, 13 35 and rotatably supported in ball bearings 19; a driving pulley 16 rigidly attached to the shaft 15; an idler pulley 17 rotatably mounted upon the end of the shaft 15 adjacent to the pulley 16; and a casing 4 detachably 40 and adjustably secured to the frame 24 and forming a support and housing for the shaft 15, bearings 19 and the gears 12, 13, 20, 25, see Figs. 3 and 6. The casing 4 is preferably formed with identical opposite 45 open ends so that the pulleys 16, 17 may be disposed on either side of the machine, and the shaft 15 is preferably provided with detachable collars 26 coacting with the ends of the casing 4 adjacent to the ball bearings 50 19 in order to prevent endwise displacement of the shaft. At the pulley end of the casing 4, a removable cap 28 is pierced by the shaft 15, the cap 28 being fastened to the end of the casing and being provided 55 with packing along the shaft 15. The opposite end of the casing 4 is closed by means of a removable imperforate cap 27 which is likewise fastened to the casing end. The interior of the casing 4 forms a grease confining chamber 23 which is accessible by virtue of a removable upper cap or cover 18 between which and the casing 4, the upper supports 22 of the shafts 7, 8 are formed. The joints between the upper ends of the 60 rolls 2, 3, the casing 4 and the cap 18 are

sealed by means of a packing 34 in order to prevent escape of lubricant from and entry of dirt to the chamber 23.

The cover 18 has an upwardly projecting integral flange 33 at its lower end, which 70 snugly fits the bottom of the beet supply chute 14 and prevents dirt from passing beneath the chute. The supply chute 14 is formed of a single piece of sheet metal having a bottom and relatively inclined 75 sides, and is supported by means of the flange 33 and a bridge element 30 which connects the sides of the main frame 24. The beet confining and guiding hopper comprises identical sheet metal plane side plates 10, 80 11 which are rigidly attached to the side elements of the main frame 24 and which may also be rigidly secured to the inclined side walls of the supply chute 14. The lower and upper edges of the side plates 85 10, 11 may be reenforced by means of angle irons, and the upper edges of the plates 10, 11 are connected by a heavy screen 29 which covers the working chamber. A pivoted distributing and rebound preventing flap 9 is suspended from a pivot rod which likewise connects the upper edges of the hopper side plates 10, 11.

During normal operation of the improved beet topper, the fluted rolls 2, 3 are 95 rotated continuously in opposite directions upon the supporting shafts 7, 8, by means of power applied to the driving pulley 16 and transmitted from the pulley 16 through the shaft 15 and gears 25, 20, 12, 13 directly to the rolls 2, 3. As viewed in Fig. 4, the roll 2 is rotated in a clockwise direction while the roll 3 is rotated in a counter-clockwise direction. The beets which it is desired to top, are supplied in bulk to the 100 supply chute 14 and advance by gravity into the space above the rolls 2, 3 and between the hopper side walls 10, 11. As the tangled mass of beets is deposited upon the rotating fluted rolls 2, 3, the individual 105 beets are segregated from the mass and are tumbled about until the tops 6 and other superfluous appendages such as roots, are eventually drawn downwardly between the cooperating ridges and grooves of the rolls 110 and are nipped from the bulbs 5 as shown in Fig. 4. The materials thus removed drop by gravity to the space between the side frames and may be removed in any convenient manner. The bulbs 5 roll along the rotating rolls 2, 3 and are thoroughly 115 scoured and cleaned being eventually discharged over the lower supports 21. While the beets are passing through the machine, the screen 29 and the flap 9 prevent excessive bouncing of the bulbs 5, the flap 9 also serving to distribute the beets in order to insure treatment of each individual object admitted to the machine.

The casing 4 may be filled with grease or 130

oil thus insuring abundant lubrication of the gears 12, 13, 20, 25 and of the ball bearings 19. The packings between the shaft 15, rolls 2, 3, the casing 4, cap 18 and cap 28 prevent escape of the lubricant from and ingress of dirt to the casing 4. The bearing between the shaft 15 and the pulley 17 may be lubricated by means of a grease cup at the end of the shaft 15, and grease cups at the ends of the shafts 7, 8 afford like means of lubricating the upper bearings of the rolls 2, 3. The lower bearings of the rolls 2, 3 are lubricated both by grease cups at the lower ends of the shafts 7, 8 and by the grease confined in the chamber 32, thus insuring abundant lubrication of all bearings of the mechanism.

It will also be noted that all of the bearings are effectively protected from dirt and injury and that similar parts are identical in structure and therefore interchangeable. The stationary supporting shafts 7, 8 are identical in structure and hence interchangeable, and this is also true of the rolls 2, 3, the side members of the frame 24, the bearings 19, the flanged collars 26 and the hopper side plates 10, 11. The plates 10, 11 and the chute 14 are formed of sheet metal which is reenforced in order to provide a rigid structure. The shaft 15 may be readily reversed in order to effect driving from the opposite side of the machine and the cap 18 permits ready access to the helical gearing and to the ball bearings 19. The entire machine may be quickly assembled or dismantled without the use of special tools and may be operated with minimum power effectively applied.

It should be understood that it is not desired to limit the invention to the exact details of construction herein shown and described for various modifications within the scope of the claims may occur to persons skilled in the art.

It is claimed and desired to secure by Letters Patent:—

1. In combination, a pair of rotary inclined rolls having cooperating surfaces formed to remove appendages from objects travelling therealong, gears associated with the upper ends of said rolls for rotating the same, a housing enclosing said gears, sealing means for preventing ingress of juice to and egress of lubricant from within said housing along said roll surfaces, and means for delivering said objects upon said rolls below said sealing means.

2. In combination, a pair of rotary inclined rolls having cooperating surfaces formed to remove appendages from objects

travelling therealong, gears associated with the upper ends of said rolls for rotating the same, a housing enclosing said gears, said housing comprising a lower lubricant confining portion and a cap detachably associated with said lower portion, packing means coacting with said lower housing portion and with said cap to prevent ingress of juice to and egress of lubricant from within said housing along said roll surfaces, and a feed plate for delivering said objects to said rolls beyond said housing.

3. In combination, a pair of stationary inclined shafts, rolls journaled on said shafts and having cooperating surfaces formed to remove appendages from objects travelling therealong, gears journaled on said shafts and associated with the upper ends of said rolls for rotating the same, a housing providing a support for said shafts and enclosing said gears, and packing means for preventing ingress of juice to and egress of lubricant from said housing along said roll surfaces.

4. In combination, a pair of stationary inclined shafts, rolls journaled on said shafts and having cooperating surfaces formed to remove appendages from objects travelling therealong, gears journaled on said shafts and associated with the upper ends of said rolls for rotating the same, a housing providing a support for said shafts and enclosing said gears, said housing comprising a lower lubricant confining portion and a cap detachably associated with said lower portion, sealing means coacting with said lower housing portion and with said cap to prevent ingress of juice to and egress of lubricant from said housing along said roll surfaces, and means extending over said housing and beyond said sealing means for delivering said objects to said rolls.

5. In combination, a pair of stationary inclined shafts, rolls journaled on said shafts and having cooperating surfaces formed to remove appendages from objects travelling therealong, gears journaled on said shaft and detachably associated with the upper ends of said rolls for rotating the same, a housing enclosing said gears and providing a support for said shafts, said housing having a portion coacting with the union between said gears and said rolls, and sealing means at said union portion for preventing ingress of juice to and egress of lubricant from said housing along said roll surfaces.

In testimony whereof, the signature of the inventor is affixed hereto.

OSWALD H. HANSEN.
